UNITED STATES PATENT OFFICE.

LEROY BAUMGARTL, OF CHICAGO, ILLINOIS.

ROOF OR FLOOR STRUCTURE.

1,140,731.

Specification of Letters Patent. Patented May 25, 1915.

Application filed October 19, 1914. Serial No. 267,480.

To all whom it may concern:

Be it known that L. LEROY BAUMGARTL, a citizen of the United States, residing at Chicago, in the county of Cook and State of Illinois, have invented a new and useful Improvement in Roof or Floor Structures, of which the following is a specification.

My invention relates, more particularly, to roofs of buildings, though not limited thereto, formed of slabs, or tile, of concrete, or other material.

It is the practice in forming roofs of slabs, or tile, to lay beams or girders in parallel relation to form supports for the slabs or tile and then apply the slabs or tile to these beams or girders to rest at their ends on the latter, each slab, or tile, partially overlapping the beam or girder and opposing the end of the adjacent slab or tile. The beams or girders are generally of structural steel with flanges, the upper flanges of the beams, or girders, providing the seating surfaces for the slabs, or tile, at the ends of the latter. In order that the slabs or tile have sufficient bearing on the beams or girders, the upper seating flanges of the latter are required to be of a greater width than is required for the desired strength of the structure and consequently the expense for beams or girders is greater than where strength alone is to be considered. Furthermore, these beams or girders are provided in relatively long spans and owing to the method of manufacture employed are more or less sinuous, as distinguished from being perfectly straight, which requires that the upper flanges of the beams or girders be of such width that such variations in the upper flanges will not reduce the seating area for the slabs, or tile, to a degree which would impair the stability of the structure. Thus the upper flanges of the beams or girders are made much wider than would be necessary if they were perfectly straight, which renders the structure comparatively costly to manufacture.

My object is to reduce the cost of such structures without sacrificing strength or stability.

Referring to the accompanying drawings: Figure 1 is a perspective view, partly sectional, of a section of a roof constructed in accordance with my invention; and Fig. 2, a perspective view of one of the similar shoes employed as a part of the structure.

In carrying out my invention I first posi-

tion upon the walls which are to carry the floor, or roof, beams or girders arranged in parallel relation, these beams or girders being spaced apart a distance substantially equal to the length of the slabs or tile which form the roof, or floor-covering and are hereinafter referred to, these beams or girders forming a framework for supporting the slabs, or tile. The beams, or girders, may be of any suitable construction, it being preferred that they be formed of steel in any desirable structural shape with flanges at their upper edges. In the particular embodiment shown these beams, or girders, represented at 3, are in the form of channels set on edge, these girders resting at their lower flanges 4 on the under structure, (not shown) and providing upper flanges 5.

After the girders 3 have been positioned as stated, shoes 6 are applied to the upper flanges 5 thereof to form seating surfaces for the ends of the slabs, or tile, represented at 7. The shoes 6, which may be of any suitable form and material, are shown as formed of concrete reinforced by wire mesh 8 extending longitudinally thereof, these shoes being of general rectangular form and provided along their under sides with channels 9 at which they are adapted to straddle the upper flanges 5 of the girders 3, thus interfitting therewith as illustrated in Fig. 1.

The tile represented at 7 are adapted to rest at their ends on the shoes 6, each tile 7 seating at its end on the adjacent shoe 6, and preferably overlapping the latter about one-half of the width of the shoe, whereby each shoe forms a bearing surface for the adjacent ends of endwise opposing tile, as represented in Fig. 1, the ends of the tile where they overlap the shoes being preferably shouldered, as represented at 10. The shoes 6 thus form the seating surfaces for the ends of the slabs, or tile, 7 and may be formed of any desirable width, it being preferred that for ordinary roof construction they be about five inches wide, which affords a seating surface for the slabs or tile of sufficient width to compensate for any irregularities or variations in the girders 3.

After placing the tile 7 as stated, the spaces between adjacent tile may be filled with elastic cement, or any other suitable material, and if desired the upper surface of the structures thus formed coated with any suitable waterproof material. It will be understood, however, that this last-referred-

to procedure is the one usually adopted where plain tile like that shown are used, and when other forms of tile are employed, this may not be a necessary step. This is, 5 however, immaterial to my invention, the novelty of which does not extend beyond the laying of the slabs, or tile.

It will be understood from the foregoing that, inasmuch as the effective seating surface for the tile is furnished by the shoes, girders or beams of a width much less than that required if the shoes were not provided, may be used and thus the cost of construction is greatly reduced.

15 It is preferred that the shoes 6, which preferably are provided in sections from two to four feet long, abut at their adjacent ends and in effect form shoes continuous throughout the length of the girders, though 20 if desired these shoes may be formed in sections of any suitable length and spaced from each other along the girders, so long as there is sufficient area provided for engagement with the ends of the slabs, or tile.

25 The use of the shoes present a further advantage in that, where the beams, or girders, are deflected, the relatively wide bearing surfaces afforded by the shoes permit of the use of mortar applied to the upper surfaces 30 thereof, or shims, for leveling the seating surface for the slabs, or tile, whereby an even floor or roof structure may be provided.

While I have illustrated and described a particular embodiment of my invention, I 35 do not wish to be understood as intending to limit it thereto, as the same may be modified and altered without departing from the spirit of my invention.

What I claim as new and desire to secure 40 by Letters Patent, is:

1. In building construction, in combination,

tion, flanged beams or girders, shoes of a width exceeding that of the beams or girders and adapted to rest on and extend along the upper surfaces thereof whereby to afford 45 an increased bearing area, and slabs or tiles spanning the space between said beams or girders with their ends bearing on said shoes.

2. In building construction, in combination, flanged beams or girders, shoes of a 50 width exceeding that of the beams or girders and adapted to rest on and extend along the upper surfaces thereof whereby to afford an increased bearing area, and slabs or tiles spanning the space between said beams or 55 girders and having shouldered ends bearing on said shoes.

3. In building construction, in combination, flanged beams or girders, shoes of a width exceeding that of the beams or girders 60 and having channels on their under sides and adapted to rest over the upper surfaces thereof and extend along the same whereby to afford an increased bearing area, and slabs or tiles spanning the space between said 65 beams or girders with their ends bearing on said shoes.

4. In building construction, in combination, flanged beams or girders, reinforced shoes of a width exceeding that of the beams 70 or girders and having channels on their under sides and adapted to rest over the upper surfaces thereof and extend along the same whereby to afford an increased bearing area, and slabs or tiles spanning the space 75 between said beams or girders with their ends bearing on said shoes.

LEROY BAUMGARTL.

In presence of—

L. HEISLAR,

A. C. FISCHER.
